UNITED STATES PATENT OFFICE.

PAUL GNATZIG, OF SUN PRAIRIE, WISCONSIN.

END-GATE FOR WAGONS.

SPECIFICATION forming part of Letters Patent No. 770,572, dated September 20, 1904.

Application filed June 15, 1904. Serial No. 212,596. (No model.)

To all whom it may concern:

Be it known that I, PAUL GNATZIG, residing in Sun Prairie, in the county of Dane and State of Wisconsin, have invented new and 5 useful Improvements in End - Gates for Wagon-Boxes, of which the following is a description, reference being had to the accompanying drawings, which are a part of this specification.

10 The object of my invention is to provide an end-gate for a wagon-box that not being hinged directly to the wagon-box is yet so mounted thereon as not to be accidentally or readily detached therefrom, that can be 15 quickly and easily swung to position on the end of the box and secured firmly in place, closing the otherwise open end of the box, and can be readily released and swung away from the end of the box to a non-interfering 20 and supported position under the box.

The invention consists of the end-gate and related parts and their combinations, as herein described and claimed, or the equivalents thereof.

25 In the drawings, Figure 1 is an elevation of a fragment of a wagon-box with my improved end - gate thereon, showing especially the means for mounting the gate and securing it in place. Fig. 2 is also an elevation at the 30 side of a fragment of a wagon-box with my end-gate mounted thereon, the end-gate being shown in the position it occupies when removed from the end of the box, a part of the box being broken away to exhibit interior 35 construction. Fig. 3 is an end view of the wagon-box with my improved gate mounted thereon, the gate being in the position shown in Fig. 2.

In the drawings, A represents a wagon-box 40 of the general form in common use, in which there is a flat bottom and upright sides. My improved end-gate is especially adapted for being applied to a box of this character, although the special form of the box is not important.

The end-gate 2 may be made of any suitable material, though ordinarily where the wagon-box is of wood the body of the end-gate would also properly be of wood, the end-gate being 50 of a size and form to fit against the ends of

the bottom and the sides of the box, thus closing the end of the box when in position thereon, as shown in Fig. 1. For protecting and strengthening the ends of the gate I advisably put angle-irons 3 3 on and across the end of 55 the gate, one flange of which angle-iron in each case fits on the outer surface of the gate. These angle-irons are secured to the gate by any suitable means. The end-gate is also provided with metal straps 4 4, which are 60 placed on the outer surface and transversely thereof at a distance apart and at the lower edge of the gate turn under it and extend beyond the inner surface of the gate a little distance and then turn upwardly, forming hooks 65 5 5, adapted to engage catches on the bottom of the wagon-box, as hereinafter described. The end-gate is mounted on the wagon-box by means of lever-arms 6 6, one at each end of the gate, which arms at one end are pivoted 70 to the gate conveniently by stud-pins 7 7, fixed in the ends of the gate at a distance from the top, but nearer the top than the bottom of the gate, which pins project outwardly through the arms 6 6 and are advisably provided with heads that prevent the arms from escaping from the pins. These arms 6 6 are pivoted medially by bolts 8 8 on the sides of the wagon-box near the bottom thereof and at a distance from the end of the box, so that 75 the arms when the end-gate is in position on the end of the box closing it are in oblique positions downwardly toward the front from the axis of their connections on the end-gate, as shown in Fig. 1. By mounting the end-gate on the wagon-box by the means and in the manner just described it can be swung by the arms 6 6, and thereby lifted and brought to position against the end of the wagon-box, as shown in Fig. 1, thus closing it, and when 80 desired by swinging the arms in the reverse direction the end-gate will be removed from the end of the wagon-box and carried down underneath the box into the position shown in Figs. 2 and 3, thus removing it entirely 85 from the end of the box, while yet supporting it thereon, but in a position that will not interfere with the loading or unloading of material into or from the wagon-box at the open end thereof. The construction and relation 90 95 100

of the parts is such that in removing the end-gate and carrying it under the wagon-box it will be carried down sufficiently far to clear the cross-bar or cleat 9, secured to the under 5 side of the wagon-box at its end for strengthening it.

For conveniently moving the end-gate to position on the end of the box and removing it therefrom and for locking it in these positions the arms 6 6 are extended beyond the bolt-pivots 8 8 and at their outer ends are each provided with releasably fastening means, which advisably consist of locking-pins 10 10, mounted in the extremities of these arms 6 6, 10 which for this purpose are each provided with a bracket 11 11, projecting outwardly therefrom and opposite to and in front of the end of the arm and through which bracket and arm registering apertures are provided, in 15 which the pins fit and are slidable endwise, the pins being held up to their work yieldingly by springs 12 12, coiled about the pins and bearing outwardly against the brackets 11 and inwardly against collars 13 13, fixed 20 on the pins. These pins are adapted to enter holes 14 therefor in holding-plates 15, fixed on the sides of the wagon-box, whereby the end-gate is locked either on the end of the box or underneath it in the positions shown, 25 respectively, in Figs. 1 and 2. The pins 10 are advisably turned over at their outer ends, forming heads for conveniently grasping them for withdrawing them from engagement with the plate.

30 The hooks 5 when the end-gate is raised and brought to position against the end of the wagon-box, as shown in Fig. 1, engage catches 16 on the end of the bottom of the wagon-box, which catches are conveniently 35 made as a part of strengthening-straps 17, fitted and secured to the inside of the sides of the wagon-box and at the bottom extending therefrom inwardly along on the surface of the bottom of the box and at the outer edge 40 of this bottom plate being turned over and downwardly on and against the end of the bottom of the box. Recesses 18 are cut in the box behind the catches 16 to receive the hooks 5 behind the catches. The plates 15 45 are advisably made in semicircular form to serve not only as holding-plates for the locking-pins 10, but also to serve as a guard or wearing plate for the lever-arms 6 to swing on and are provided with transverse diametrical members which fit against the box under the lever-arms 6 6 and about the pivot-bolts 8.

50 What I claim as my invention is—

1. In combination, a wagon-box, an end-

gate adapted to fit against the end of the box, arms pivoted to the ends of the gate and to the sides of the box at a distance from the end-gate and below the horizontal planes of the pivoting on the end-gate when the gate is in place on the end of the box, and means on the arms and complementary means on the box for locking the arms in position to hold the gate in place on the end of the box.

2. In combination, a wagon-box, a gate adapted to fit against the end of the box, arms pivoted to the ends of the gate and to the sides 60 of the box at a distance from the gate and below the horizontal plane of the pivoting on the gate when the gate is in place on the end of the box, extensions of said arms beyond their pivoting on the box, and means on said 70 extensions for locking them holding the gate in position on the end of the box and removed therefrom.

3. In combination, a wagon-box, an end-gate, arms pivoted to the ends of the gate medially and to the wagon-box adapted to swing the gate to place against the end of the box and rearwardly away and downwardly therefrom to substantially horizontal position under the box, and means on the arms and box 80 for locking the arms and holding the gate against the end of the box and beneath the box.

4. In combination, a wagon-box, an end-gate, arms pivoted to the ends of the gate and to the wagon-box adapted to swing the gate 85 to place against the end of the box and rearwardly and downwardly therefrom to position under the box, hooks extending inwardly on the lower edge of the gate, catches on the bottom of the box adapted to be engaged by said 90 hooks upwardly, and means on the arms and box for locking the arms in place when the gate is against the end of the box and when it is beneath the box.

5. In combination, a wagon-box, an end-gate, arms pivoted to the ends of the gate and to the sides of the box at a distance from the gate, extensions of said arms beyond their pivoting to the box, spring-actuated locking-pins 100 in said extensions, holding-plates on the box 105 having holes adapted to receive said locking-pins, hooks on the end-gate, and catches on the bottom of the box adapted to be engaged by said hooks.

In testimony whereof I affix my signature in presence of two witnesses.

PAUL GNATZIG.
